UNITED STATES PATENT OFFICE

2,654,370

SMOKING PIPE

Robert Lequeux Smith, Portsmouth, Va., assignor
of one-sixth to A. B. Bowman, San Diego, Calif.

Application January 5, 1949, Serial No. 69,297

1 Claim. (Cl. 131—213)

1

My invention relates to a smoking pipe, and more particularly to improvements over the subject matter of my former application for Letters Patent, Serial No. 659,352, filed April 3, 1946, now Patent No. 2,628,622, issued February 17, 1953, and the objects of my invention are:

First, to provide a pipe of this class which is generally simplified as compared to the structure of said former patent application, and which is very efficient in condensation of volatile fluids and cooling of the smoke passing through the pipe;

Second, to provide a pipe of this class which is very simple and easy to service;

Third, to provide a pipe of this class having a tobacco filter basket which is very simple and easy to remove and install when cleaning the pipe;

Fourth, to provide a pipe of this class which assumes conventional proportions, and is substantially equal in weight to conventional smoking pipes;

Fifth, to provide a smoking pipe of this class which greatly protects the health of the smoker by removing harmful nicotine-bearing volatile fluids from the smoke passing into the smoker's mouth;

Sixth, to provide a smoking pipe of this class which employs a very simple reverse flow diverter, which considerably lowers the temperature of volatile fluids, permitting the same to be readily condensed and collected in the tobacco contained in the filter basket; and

Seventh, to provide a smoking pipe of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claim, reference being had to the accompanying drawing and to the characters of reference thereon, forming a part of this application, in which the figure of the drawing is a longitudinal vertical sectional view of a smoking pipe, shown on enlarged scale, and illustrating by arrows the flow of smoke or fluid through the pipe.

Similar characters of reference refer to similar parts and portions throughout the drawing.

The bit 1, tube 2, basket 3, diverter 4, stem 5 and bowl 6 constitute the principal parts and portions of my smoking pipe.

The bit 1 is a substantially conventional pipe

bit, having a bore 1a therein, communicating with an enlarged bore portion 1b, in which the normally rear end of the tube 2 is fitted. This tube 2 is a hollow cylindrical metal tube, preferably made of aluminum or the like, and slidably positioned therein is the basket 3, which is provided with a perforate bottom 3a and clip end portions 3b, engaging the forward open end 2a of the tube 2. Surrounding the tube 2 is a cup-shaped diverter 4, which at its open end 4a is externally fitted over the forward end 1c of the bit 1, internally of the hollow cylindrical stem 5. Near the forward end of the bit 1 the diverter 4 is provided with openings 4b in the side wall thereof, adapted to admit smoke internally thereof, adjacent the tube 2. It will be noted that the difference in diameter between the tube 2 and diverter 4 provides an annulus between the same for the passage of smoke forwardly to the forward end 2a of the tube 2, the forward end of the diverter 4 is closed at 4c, adjacent the pipe bowl outlet passage 6a. The bowl 6 may be made of any suitable material, as desired, and externally fitted on the shank 6b thereof is the externally finned stem 5, which is a hollow cylindrical metal stem, having its rear end portion 5b surrounding the enlarged diameter portion of the bit 1. The basket 3 is adapted to contain a filtering element, preferably tobacco, for the purpose of straining the smoke passing therethrough, preliminary to the passage thereof into the bore 1a of the bit 1. It will be noted that the transition of the reduced bore 1a into the enlarged bore 1b provides a trap for saliva which may travel forwardly in the bore 1a, whereby such saliva is absorbed in the tobacco within the basket 3 and prevented from returning and carrying nicotine to the smoker's mouth through the bit 1.

The operation of my pipe is substantially as follows: When the smoker draws smoke from the bowl 6 through the passage 6a, the smoke travels as indicated by arrows around the closed end 4c of the cup-shaped diverter 4, and in the space between the cylindrical wall portion of the diverter 4 and the stem 5. The tolerance intermediate the diverter 4 and stem 5 is limited so that efficient removal of the heat from the smoke and condensing the volatile fluids bearing nicotine is accomplished. After the smoke is passed rearwardly around the diverter 4, it travels inwardly through the openings 4b and along the outer wall of the tube 2, where additional condensing and cooling takes place, the smoke then passes as indicated by the arrows through the basket 3 containing the tobacco A, or other suit-

able filtering medium, as desired. After passing through the tobacco A the smoke passes through the perforate end 3a of the basket 3 and into the enlarged bore portion 1b at the transition with the bore portion 1a through which the smoke finally passes to the smoker.

It will be noted that saliva which may gradually travel through the bore 1a drops by gravity into the enlarged bore portion 1b and is absorbed by the tobacco A in the basket 3, preventing the same from returning laden with nicotine to the mouth of the smoker.

When it is desired to replace the tobacco A in the basket 3 and clean the pipe, the bit 1 is removed from the interior of the stem 5, then the diverter 4 is removed from the end of the bit 1, the clip ends 3b are then removed from the tube 2, and the tobacco is carried therewith out of the tube 2 and replaced by fresh tobacco. All of the liquid condensed in the diverter 4 and the stem 5 may be drained when the bit 1 is removed from the stem 5.

Though I have shown and described a particular construction, combination and arrangement of parts and portions, I do not wish to be limited to this particular construction, combination and arrangement of parts, but desire to include in the scope of my invention the construction, combination and arrangement substantially as set forth in the appended claim.

Having thus described my invention, what I claim as new and desire to secure by Letters Patent is:

A pipe having a hollow stem, and a bit provided with an enlargement and having an end in the stem, a smoke diverter comprising a tube extending within said hollow stem and having a closed end therein and an open end in frictional engagement over the end portion of the bit in the stem, and having apertures adjacent the

open end for passage of smoke therethrough, an open ended cylindrical member having a diameter less than that of the diverter and adapted to be mounted within said enlargement in said end of said bit and extend into said diverter, and means adapted to support a filter within the cylindrical member comprising a perforated planar bottom having clip legs located at the outer periphery and perpendicular to the plane thereof, said legs terminating in relatively short outwardly directed portions adapted to abut the edge of the free end of the cylindrical member to position said disk so that it lies in the plane of the other end of the cylindrical member.

ROBERT LEQUEUX SMITH.
